GAITER OR SIMILAR ARTICLE

Thomas Henry Doherty, South Bend, Ind., assignor to Mishawaka Rubber and Woolen Manufacturing Company, Mishawaka, Ind., a corporation of Indiana

Application June 20, 1955, Serial No. 36,577

Term of patent 14 years

(Cl. D17—3)

Fig. 1 is a front perspective view of a gaiter, or similar article showing my new design;

Fig. 2 is a view similar to Fig. 1 showing the fastener in the released position and showing only a fragmentary portion of the dotted line gaiter of Fig. 1;

Fig. 3 is an enlarged front view of the fastener of Fig. 1 with only a fragmentary portion of the dotted line gaiter; and

Fig. 4 is a view taken on the line 4—4 of Fig. 3.

The dominant features of my design reside in the portions shown in full lines.

I claim:

The ornamental design for a gaiter or similar article, as shown and described.
